GAME OF SKILL

Erwin Bengner, Breslau, Germany; vested in the
Alien Property CustodianApplication December 31, 1936, Serial No. 118,644
In Germany January 27, 1936

10 Claims. (Cl. 273—119)

This invention relates to a game of skill and particularly one wherein prizes in the form of merchandise may be delivered to the winner and which may be used in combination with a coin controlled vending machine.

The object of this invention is to improve the efficiency of games of skill of this type, by providing such game with a movable carriage having a number of prize pockets into which a ball struck as a target by means of a striker or hammer can be successively thrown as a result of which different prizes according to the win pocket will be delivered.

Another object of this invention is to provide a game of this type whose manufacture will be relatively simple, practical and of low cost.

On embodiment of my invention is illustrated in the accompanying drawings which constitute part of this specification and in which similar reference characters denote corresponding parts,

Fig. 1 is a side elevation of the game forming the subject of this invention, the cabinet being shown in vertical section;

Fig. 2 is a fragmentary section on line IV—IV of Fig. 3 similar to that of Fig. 1 showing the cabinet and carriage in cross sections;

Fig. 3 is a cross section on line III—III of Fig. 1 of the device;

Figs. 4—6 show three different positions of a member for operating movable impediments in the prize pockets of the carriage forming part of this game device; and

Fig. 7 is a rear view of the device with the rear wall of the cabinet removed showing the coin controlled means for locking and releasing the carriage, the means for lifting the ball into operative position and the means for releasing the prize compartment.

Fig. 8 is a vertical section on line VIII—VIII of Fig. 3 and

Fig. 9 is a cross section on IX—IX of Fig. 7.

Referring to the drawings more in detail, the game comprises a casing or cabinet 4 which in its upper portion contains a carriage 9 mounted on rails 8, 8 and provided with a plurality of trough shaped elongated pockets 10 (Fig. 3) and an initial pocket 10' arranged parallel to the side walls of the cabinet and to one another (Figs. 1, 2 and 3). These pockets 10, and 10' are separated from one another by open spaces or passages 14', 14², 14³, 14⁴ and 14⁵ and are displaced longitudinally relative to one another and transversely to the cabinet each by one half the length of a pocket (Fig. 3). The width of said passages between the different pockets varies, the narrowest one 14'

being between the pocket 10' and the adjacent pocket 10, thence gradually increasing in the direction from right to left with reference to Fig. 3. The game also comprises a hammer 1 which is oscillatorily suspended to swing in a vertical plane, as will be hereinafter more fully described, so that when operated will be capable of striking a ball admitted to a pocket and located just opposite said hammer. The rails 8 on which the carriage is movably guided extend obliquely relative to the side walls of the carriage and relative to the plane of oscillation of the hammer.

The free spaces or passages 14' to 14⁵ inclusive between the different pockets are closed both in front and rear by upstanding partitions or walls arranged parallel to themselves and to the striking plane of the hammer. The front, lower partitions 15 extend between adjacent pockets, closing the gaps between the same, and the rear higher partitions 16', 16², 16³ and 16⁴ are each arranged in alignment with and extend over the rear end edges of the corresponding pockets serving also as rear walls thereof. Thus partition 16' closes the rear of the opening 14⁴ and that of the pocket farthest apart from hammer 1, partition 16² closing the rear of the opening 14³ and that of the next pocket, etc.

The openings 14', 14², 14³, 14⁴ and 14⁵ each lead into a ball trap 17 which leads to a gravity actuated lever mechanism 42 indicated in Figures 2, 7 and 8, and thence into the ball collecting channel 51 from where the ball after the operation of a coin controlled actuating lever 50 will be lifted in well known manner back by a ball lifter 55 into operative position in front of the hammer 1.

The bottom of each trough shaped pocket 10, is sloping downwardly toward the front, each terminating into an opening 12 communicating through a chute or duct 52 with a channel 53 of a corresponding drawer 54 containing the prize to be won by the successful player. The ball entering said channel 53 acts as a coupling element between a pull member 54' and a drawer 54 to permit the withdrawal of said drawer 54, shown in Figures 1 and 9, as will be hereinafter described.

For feeding the carriage, a lever 18 is provided, which is suitably fulcrumed as at 18' to a stationary part of the cabinet to oscillate in a horizontal plane and project outward through a slot 4a in the front wall of the cabinet. This lever is adapted to engage a pin 9a or the like provided on the underface of the carriage whereby it will feed the carriage in the direction of the arrow

(Fig. 3). The stroke of the lever 18 is limited by the length of the slot 4a through which it projects from the wall of the cabinet or the machine. A tension spring 19 between the cabinet and said carriage tends to return the latter to its initial position.

In its position the carriage 9 is adapted to be locked by a pawl 21 cooperating with a series of notches 20 provided in the rear edge of the carriage 9 (Fig. 3). This pawl is adapted to be actuated by means of a rod 27 in the following manner:

Slidably guided in vertical direction in the cabinet is a lifting bar 22 provided at its upper end with a nose 22' (Fig. 1). Extending parallel to said bar 22 is a vertically movable cocking rod or bar 24 which under the action of a tension spring 25 normally tends to move into raised position. This rod 24 has a projection 23 extending in the path of the nose 22' adapted to engage said projection 23 when the bar 22 is moved downwardly and thereby move the cocking rod 24 downwardly against the tension of its spring 25. The downward movement of bar 22 can be effected by the actuating lever 50 which as hereinabove described may be coin controlled. The upper end of the rod or bar 24 is adapted to bear against a spring actuated member 26 rotatively mounted on a longitudinal shaft 3 extending transversely through the cabinet and one end of which carries a knob 5. Connected to said member 26 is one end of a rod 27 the other end of which is connected to the pawl 21. While when the actuating lever 50 is released the rod 22 can return to its raised position, the depressed rod 24 becomes locked in cocking position by a spring actuated locking member 28 capable of engaging an aperture 24' thereof and which when released will permit the cocked rod 24 under the action of its spring 25 to shoot upwardly and acting against the member 26 turn the latter on the shaft 3. Normally the rod 24 acting against member 28, will cause rod 27 to hold the pawl out of engagement with the carriage 9. But when the rod 24 is depressed and locked by locking member 28 the member 26 under its spring force will cause the rod 27 to pull the pawl 21 into operative position locking the carriage 9.

The carriage is adapted to remain in locked position until the ball 7 drops onto the lever 42 and by gravity causes the release of said locking member 28. At that instant the released rod 24 shoots upwardly and acting on member 26 will turn the latter so that rod 27 will bring the pawl 21 into inoperative position.

The ball lifter 55 is actuated from the rod or bar 22, when the latter is moved downwardly through the operation of the coin controlled actuating lever 50, to sweep the ball 7 from the collecting channel 51 into operative position. A second rod mechanism 29 is suitably connected to the gravity actuated lever mechanism 42 and also to the push member 30 so that when the latter is pushed inwardly the locking member 28 will be released from engagement with the rod or bar 24, as a result of which the latter will be permitted to return into its raised position to unlock the carriage 9 as hereinabove described. The unlocked carriage will be permitted to return into initial position under the action of its spring 19 (Fig. 9).

To prevent the carriage 9 from moving too speedily under the action of its spring 19 the front edge thereof is formed to a rack 9a with

which mesh gears 31 (Fig. 3) which tend to retard said movement.

Provided on the underside of the carriage 9 and extending on a bias parallel to the direction of movement of said carriage and in alignment with the pins 13 is a slidably guide bar 33 which under the action of a spring 32 tends to hold said bar 33 in the initial position shown in Figs. 1 and 4. This bar 33 can be manually operated from the push member 30 projecting outwardly from the side of the cabinet. The bar 33 is provided with notches 34 adapted to engage and support the pins 13 slidably bearing in the individual pockets 10, and which by gravity or spring action tend to move downwardly (Figures 4 to 6). The side edges 34' of these notches are bevelled in the direction of the feed movement of the carriage 9 and serve as guides for said pins. In the initial position of said bar 33 and carriage all stop pins 13, except one, are in the lowered positions engaging the notches 34, while pin 13 in the pocket nearest the initial pocket 10' is raised resting on the bar 33, and thus forms an obstruction to prevent the ball 7 on being landed in said pocket from dropping through the opening 12.

If the bar 33 is slightly pushed inwardly by member 30, the raised pin 13 slides down the guide 34' into the corresponding notch 34 (Fig. 5), permitting the ball 7 to drop through the aperture 12, whence it passes through a duct 52 into the channel 53 of a drawer 54 containing the prize to be won by the successful player as hereinabove described. When the delivery drawer has been emptied and returned to its closed position, the ball 7 is allowed to drop into the channel 51 in front of the ball lifter 55, which after insertion of another coin can be again actuated through the rod 22 to lift the ball once more into the operative position.

However, if the winner prefers to take another chance for a greater stake, he shifts the carriage from its initial position by means of the feed lever 18. By said shifting of the carriage relative to the bar 33 all pins 13 are lifted into obstructing position, as shown in Fig. 6.

The hammer 1 is oscillatorily suspended by a leaf spring 35 from the shaft 2 horizontally borne in a stationary frame 36. This shaft 2 by lever arms 6, 6', 6² is operatively connected to the manually operable shaft 3 carrying the knob 5. The frame 36, which for practical reasons may be composed of two separable sections, is provided in its rear face with a horizontal slot 37 (Fig. 7) through which projects the rear end 18' of the feed lever 18. The length of the slot 37 can be regulated by a screw 38 to control the stroke of the lever 18.

Pivoted at 39a to the frame 36 in a vertical plane is a double armed lever 39 whose lower arm 39b extends over the slot 37 and lies in front of the rear end 18' of the lever 18 (Fig. 7) while its upper arm carries a pin 40. When this lever 18 is swung its extended end 18' will swing the lever 39 around its pivot 39a and cause its pin 40 to strike against the arm 6 of the levers mechanism 6, 6', 6² and thereby swing the hammer 1 in the direction of the full line position (Fig. 1) and to hold it raised sufficiently to permit the upstanding walls 15 of the carriage to pass underneath said hammer. When the feed lever 18 is released, the hammer 1 automatically returns by gravity into its initial position.

To prevent the hammer 1 from impeding the return of the carriage the suspension of the ham-

mer 1 from the shaft 2 is such that it can yield transversely to the striking plane of the hammer as indicated by the dotted lines in Fig. 1, while a spring 41 tends to return it into the perpendicular position to lie exactly in front of the ball 7 5 located in a pocket 10 or 10'.

The operation of the machine is as follows:

In initial position the carriage 9 is locked by pawl 21 against the inner face of the side wall of the cabinet 4 and all pins 13 except one in pocket 10 nearest to initial pocket 10' are lowered (Fig. 4).

On the insertion of a coin through a slot the actuating lever 50 can be operated so as to lift a ball 7 from the collector channel 51 into the 15 visible initial position in the pocket 10' to lie in front of the hammer 1. By turning the shaft 3 by means of its knob 5 the hammer 1 can be swung through the medium of the levers 6, 6', and 6² to strike the ball in the direction of the pockets 10. The object of the game is to land the ball 20 into the pocket nearest to the initial pocket 10'. If the blow exerted on the ball is too strong the latter will miss the pocket, drop into the ball trap 17 whence it will pass onto lever 42 and by gravity 25 actuate the locking member 28 causing the release of the carriage and then drop into the collector channel 51. If the blow is too weak, the ball will land into the opening 14' whence it likewise rolls into the collector 51.

In both instances the player loses the game.

If he wishes to try again his skill he must insert a new coin to render the machine operative.

If, however, the blow is of the proper strength the ball will be landed into the pocket 10, next to 35 the initial pocket 10' where it will come to rest at the raised stop pin 13. The player now can take the prize which, for example, may be merchandise of a certain value, say of the value of the inserted coin or coins. This is effected by first operating the push member 30 whereby bar 33 is displaced causing the stop pin 13 to be lowered (Fig. 5), as heretofore described, as a result of which the ball will be permitted to drop into the channel 53 in which acting as coupler in well known manner it will permit the withdrawal of drawer 54 containing the allotted merchandise. When the drawer is released the ball 7 will be permitted to drop into the collecting channel 51 from which upon insertion of a new coin it can be again lifted into operative position as aforescribed.

But the player need not take the prize won by landing the ball into the first pocket 10. He has a choice to play the game for a larger stake by attempting to throw the ball from the first win pocket into the adjacent second pocket 10'. To this end he must first unlock the carriage by push member 30 and lever 29, then displace the carriage 9 from its initial rest position in the direction toward the hammer so as to bring the said win pocket into the position previously occupied by the initial pocket 10'.

This movement of the carriage is effected manually by means of the lever 18, whose rear end 18² acting on lever 39 lifts the hammer 1 temporarily to permit upstanding walls 16 of the carriage to pass. On the release of the lever 18 the hammer 1 by gravity returns into the perpendicular operative position.

Now, the player, as before, will swing the hammer 1 through operation of the knob 5 in an attempt to land the ball into the second pocket for a higher stake. If he succeeds he proceeds as before by operating the push member 33 to lower

pin 13 as a result of which the ball is permitted to drop down through opening 12 into channel 53 of the drawer 54 containing the higher prize.

In a similar manner the player may choose to try his skill with the next pocket for a still higher stake, and after that with a farther pocket and so on.

It is evident that the correct striking of the ball becomes more difficult progressively at each step, because, as already mentioned, the free spaces 14', 14², 14³, 14⁴ and 14⁵ separating the pockets 10 from one another become larger at each step.

I claim:

1. In a game of skill, the combination with a coin controlled machine having compartments containing prizes of different value, of a stationarily supported manually operable striking element, a ball serving as missile for said element, a manually operable carriage displaceable at an angle relative to the striking plane of said element and having a plurality of prize determining pockets capable of receiving the ball when projected by said element, said pockets being separated by open spaces and arranged in a staggered relationship with respect to the striking plane of said element, a ball collecting channel communicating with said open spaces, compartments for holding the prizes, said pockets having discharge openings communicating with said different prize containing compartments, movable impediments in said pockets to hold the ball in the pocket for a successive stroke therefrom into the next adjacent pocket, means for locking said carriage in position, means for lifting the ball from said ball collecting channel into operative position in front of said striking element, means for releasing the prize holding compartments and means for simultaneously operating said locking means, and ball lifting means.

2. A game of skill comprising a striking element, a missile for said element, a carriage having a plurality of targets for said missile arranged in staggered relationship with respect to the striking plane of said element at successively remoter distances from the striking point thereof, said carriage being capable of displacement in a direction toward said element so as to successfully position one of its targets at a time to be in range with the striking plane of said element.

3. A game of skill comprising a striking element, a ball serving as missile for said element, a carriage having a plurality of pockets serving as targets to receive said ball, said pockets being arranged in staggered relationship with respect to the striking plane of said element at successively remoter distances from the striking point thereof, said carriage being capable of displacement in a direction toward said element so as to successfully position one of its pockets at a time to be in range with the striking plane of said element.

4. A game of skill according to claim 2 in which means are provided for the stepwise displacement of said carriage.

5. A game of skill according to claim 2 in which 65 said targets are separated by open spaces and there are provided a missile collector below said open spaces and means for returning said missile from said collector into operative position in front of said striking element.

6. A game of skill according to claim 3 in which 70 75 are provided moveable impediments in said pockets capable of retaining the ball in a pocket for a successive stroke therefrom into the next adjacent pocket.

7. A game of skill according to claim 2 in which means are provided for moving said carriage at an angle relative to the striking plane of said element.

8. A game of skill according to claim 3 in which a manually operable horizontal shaft is supported above the carriage and said striking element is oscillatorily suspended from said shaft to swing transversely of said pockets.

9. A game of skill according to claim 2 in which are provided means for causing the automatic locking of said carriage in adjusted position and means for unlocking the same prior to its displacement.

10. A game of skill comprising a striking ele- 15

ment, a missile for said element, a displaceable carriage having a plurality of pockets capable of receiving said missile, said pockets being arranged in staggered relationship with respect to said element, and separated at successively remoter distances from one another by open spaces, moveable impediments in said pockets to retain the missile in a pocket for a successive stroke therefrom into the next adjacent pocket, means for the stepwise displacement of said carriage with respect to the striking plane of said element, means for locking said carriage in adjusted position and means for the simultaneous operation of said impediments and said locking means.

ERWIN BENGNER.
